[57] CLAIM

The ornamental design for a open end spectacle case, as shown and described.

DESCRIPTION

FIG. 1 is a front elevational view of an open end spectacle case showing my new design;

FIG. 2 is a front perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof; and

FIG. 8 is a left side elevational view thereof.

FIGS. 2-9 are shown without corrugations for ease of illustration.
